DESIGN FOR AN ASHTRAY OR SIMILAR ARTICLE

Horace A. Fuld, New York, N. Y.

Application June 9, 1939, Serial No. 85,415

Term of patent 7 years

To all whom it may concern:

Be it known that I, Horace A. Fuld, a citizen of the United States of America, residing in New York city, in the Borough of Manhattan, county and State of New York, have invented a new, original, and ornamental Design for an Ashtray or Similar Article, of which the following is a specification, reference being had to the accompanying drawing, forming part thereof, wherein

I claim:

The ornamental design for an ashtray or similar article, substantially as shown.

HORACE A. FULD.
